UNITED STATES PATENT OFFICE.

WALTER HENRY PEARCE, OF SUMMIT, NEW JERSEY.

VALVE-GRINDING TOOL.

1,131,789.

Specification of Letters Patent. Patented Mar. 16, 1915.

Application filed October 8, 1913. Serial No. 793,132.

To all whom it may concern:

Be it known that I, WALTER HENRY PEARCE, a citizen of the United States, residing at Summit, county of Union, and State of New Jersey, have invented certain new and useful Improvements in Valve-Grinding Tools, of which the following, taken in connection with the accompanying sheet of drawings, is a full, clear, and concise description.

My present invention more specifically comprehends an automatic valve grinding tool of the screw driver type provided with means for regulating the degree or extent of rotation, which the tool may impart to the valve upon its seat in order to prevent the formation of grooves or pits on either the valve or its seat by the abrasive material employed in the grinding process. In order to accomplish this result the extent of rotary movement imparted to the tool and the valve during the effective operating movement of the tool is less than a circle or complete revolution. I accomplish this result by a combination of coöperating parts which produce a regularized differential movement in opposite directions of rotations of the tool. Each alternative movement of the tool is movements in the same direction being uniform in extent but the successive movements in opposite direction varying in degree, the active grinding movement being the lesser of the two. Both movements are caused by the reciprocation of a hand grip and associated parts along the spirally grooved body of the tool. The object of regulating the extent of active valve grinding movement to less than a complete circle or revolution is as explained to prevent the formation of minute circular grooves or of pits in the valve or its seat by the abrasive compound which frequently occur during ordinary grinding processes as now practised with known tools. It will be apparent that by imparting to the valve a partial rotation such an objectionable condition cannot result, because the initial point at which the abrasive action begins and the point at which it ends on each active rotation of the tool are separated, leaving an intermediate zone which cannot be traversed by abrasive grit, which through adhesion to the valve may be carried by it.

To the accomplishment of this desirable function my tool has been designed and it essentially comprises a means whereby the

reciprocating hand grip is so formed as to provide for a degree of lost motion on its active or downward stroke, which imparts to the tool the partial working rotation referred to, while on the inactive or upward stroke no lost motion occurs and the tool is made to rotate in the reverse direction slightly beyond a complete circle or full rotation. Thus the active working movements while causing a grinding or abrasive action between the entire valve upon its seat, prevents any abrasive grit from traveling from that zone of contact represented in a circle by the extent or degree of rotary movement of the tool into that zone or segment of the circle represented by the difference between the initial starting and finishing points in the movement of the tool.

In the drawings accompanying this specification I have shown a preferable embodiment of my invention, said form being illustrated rather than definitive, since modifications and changes might easily be made or resorted to without departing from the spirit of the invention.

Figure 1 illustrates the tool in practical operation associated with a valve of a gas engine, so much of the latter being shown as will serve to afford a complete understanding of the construction and operation of the tool. Fig. 2 is a fragmentary detail of the reciprocating hand grip illustrating the lost motion mechanism. Fig. 3 is a sectional view thereof taken on lines A—A of Fig. 1 together with a diagrammatic chart illustrating the progressively shifting points of inauguration and terminus of the grinding or alternate working movements of the tool. Fig. 4 is a fragmentary detail partly in section illustrating a modification including a detail spring arrangement for providing against free reverse rotation of the lost motion guide sleeve, and Fig. 5 is a cross-sectional view taken on line B—B of Fig. 4.

In detail the tool consists of a conventional screw driver consisting of a shank portion 1, provided at its lower extremity with an enlarged flattened end 2 and at its upper end the hand grip or knob 3. The valve engaging end 2 and the shank portion 1 being made separable parts suitably fastened together as shown and in working unison while the hand grip 3 is permitted to remain stationary under the grip of the user while the active working parts of the tool moves. The shank 1 is provided with

spiral grooves 4 encircling the shank in one revolution in which operate, pins or lugs formed on the ends of screws 5 and 6 and carried by the sleeve 6^a for imparting the desired rotary motion of the tool. The above is descriptive of a conventional so-called automatic screw driver which is well-known in the art. To this conventional form of screw driver I have applied my lost motion reciprocal hand grip which while operating in the same manner as reciprocal hand grips of the described well-known screw driver type, imparts the described movements to obtain the desirable results heretofore pointed out. This reciprocating hand grip when made in accordance with my invention and when embodied in the specific illustrated form shown consists in providing the sleeve 6^a or an independent segmental sleeve 7 fast thereto with two series of oppositely disposed serrations of saw-tooth formation, the teeth 8 of one series being disposed at a different angle or incline to the teeth 9 of the opposite series, said teeth 8 and 9 being substantially at right angles to each other, but separated and terminating in staggered relation. Each tooth of each series has an angular guide face 10 and a rectilinear guide face 11, the latter being parallel to the axis of the tool and in line with the center of the angular guide face 10 of a tooth of the opposite series, this for the purpose of guiding the guide pin 12 carried by the sleeve 13. The sleeve 13 serves as a hand grip for the operator of this described mechanism which constitutes the lost motion mechanism whereby the differential rotary movements are attained.

In the illustrated embodiment, I have provided two series of six teeth each and the tool in operating on what I have termed its working stroke, that is the effective grinding stroke, the guide pin 12 is caused to move, as will be explained more fully later, from its upper position in engagement with the teeth of the upper segment of the lost motion sleeve 7 as indicated at 14 to the lower position as indicated at 15 in a path indicated in Fig. 2. In this downward movement the pin 12 engages the angular or incline guide face 10 of a lower tooth imparting thereto a partial rotary movement, this movement being imparted to the sleeve 6^a causes the pins or projections 5 and 6 to move along the groove 4 of the shank without rotating the latter. This constitutes lost motion in the operation of the device. While the segmental sleeve 7 is provided with six uniform teeth, more or less teeth may be employed and the degree of rotation of the tool correspondingly regulated. The sleeves 6^a, 7 and 13 all move together when the pin 12 engages the low part between the teeth of the lower segment causing the pins 5 and 6 to travel along the remaining portion of the groove 4 rotating the shank 1 accordingly. When the reciprocating hand grip is moved upwardly along the shank, no lost motion takes place but rather a greater degree of rotation is imparted to the tool end, as will presently be explained.

In order to cause the pin 12 during the operation of the tool to progressively travel from between alternate teeth of the two segments of the segmental sleeve 7 in one direction and to prevent an independent free movement or rotation of the sleeve 7 and sleeve 13, when the guide pin 12 is in a neutral position between the series of teeth as indicated by the line C—C of Fig. 2, in an opposite direction I provide within the lower extremity of the sleeve 13 a spring 16 which frictionally bears against the lower segment of the sleeve 7, the surface of which is provided with indentations 17 into which the end of spring, by reason of its inherent tension snaps confining the sleeve 7 to a relative movement in the direction of the arrow (see Fig. 5). The pin is therefore forced to travel the path indicated in Fig. 2.

The operation of the tool is substantially as follows: The hand of the operator grasping the knob 3 by one hand and the sleeve 13 with the other hand causes the latter and its associated parts to reciprocate along the stem of the tool, the tool end of which is operably connected to the valve to be ground. Assuming that the reciprocable part is at the extreme upward limit of its movement. Pressure upon the sleeve 13 exerted in a downward direction will cause the guide pin 12 to move from its position in engagement with the serrated upper segment of the sleeve 7 (which position is indicated at 14 in Fig. 2) downwardly into engagement with the incline surface 10 of a tooth of the lower segment. Continuous movement of the sleeve 13 will cause the pin 12 to partially rotate the segmental sleeve 7 until the pin 12 reaches the lower end of the incline and abuts the wall of an adjacent tooth. This partial rotary movement is, of course, transmitted to the guide pins 5 and 6 which travel in the groove 4 of the tool shank without rotating the latter. Owing to the fact that the series of teeth are in staggered relation and are six in number in each series, the pin rotates the sleeves 6^a and 7, one twelfth of the circumference of the shank 1, of the tool without causing it to rotate. Continued movement of the sleeve 13 along the shank cause the segmental sleeve 7 to move downwardly with it in rectilinear direction the remaining eleven twelfths of the remaining or untraversed portion of the shank. Assuming that the flattened end of the screw driver is in the

initial position indicated at α in the diagrammatic illustration Fig. 3, downward movement of the sleeves 13 and 7 will cause the valve to rotate until the sleeve 7 abuts the limiting stop x . The position then of the flattened end 2 of the tool and the slot in the valve at the end of this stroke is at b (see Fig. 3). In this manner, the valve has been rotated on its seat eleven twelfths of a complete revolution. On the upward inactive stroke or reciprocable movement of the gripping sleeve 13 and its associated parts, no lost motion occurs. In this stroke the pin 12 will move from its lower position indicated at 15 (Fig. 2) and abut the incline 10 of an upper tooth. Continued movement will cause the sleeves 6^a and 7, carrying pins 5 and 6 to traverse the entire length of the shank until the limiting stop x is reached, causing a complete revolution of the tool end 2. Continued upward pressure will cause the pin 12 bearing against the incline 10 to partially rotate the sleeves 6^a in reverse direction which in turn through pins 5 and 6 causes the tool to move with it thus rotating the tool a one twelfth degree beyond the complete circle, the valve in this movement being disengaged from its seat under the action of a spring y which lifts the valve when pressure is removed from the tool, (the valve assuming the position shown in dotted lines in Fig. 1). As explained, no lost motion takes place in this upward movement of the sleeve 13, the pins 5 and 6 being forced to travel the entire length of the grooves 4 and then the sleeves 6^a and 7 causing it to rotate slightly further to transcribe more than a complete revolution in a reverse direction, as indicated in the diagram, the travel of the flattened end 2 of the tool and the slot in the valve being indicated from b to c . The next succeeding downward movement of the sleeve and associated parts in which movement the lost motion described again occurs will cause the tool and valve to rotate to the position indicated at d . Thus it will be seen that the working rotary movements of the valve upon its seat are partial rotations, in no instance a complete revolution thus resulting in perfect grinding and producing highly finished surfaces on valve and seat.

Having thus described my invention what I claim as new herein and desire to secure by Letters Patent is:

1. A valve grinding tool comprising a spirally-grooved shank, a valve-engaging end and reciprocating means coöperating with the grooved shank and adapted to impart to the valve-engaging end regularized differential, opposite rotary movements.
2. A valve grinding tool comprising a spirally-grooved shank, a valve-engaging end and reciprocating lost motion means

coöperatively associated with said grooved shank and adapted to impart to said end partial pre-determined rotary movement, when reciprocated in one direction, and a greater pre-determined rotary movement when reciprocated in an opposite direction.

3. A valve grinding tool, comprising a spirally grooved shank, handle and tool ends, a member adapted to impart rotary movement to the shank and tool end, said member including lost motion mechanism, said lost motion mechanism operating to cause a partial ineffectual movement of the member along the shank in one direction.

4. A valve grinding tool, comprising a grooved shank provided at one end with a handle, and at its opposite end with a tool, adapted to coöperate with a valve to be ground, reciprocating means coöperating with the grooved shank for operating the tool, said reciprocating means, being provided with a lost motion mechanism, whereby the reciprocating member may be moved along the grooved shank a predetermined distance in one direction before being brought into effective working position, so as to impart thereto partial rotary movement, said member adapted when moved rectilinearly in the opposite direction to impart a greater rotary movement to the tool in reversed direction.

5. In a tool of the character described, a grooved shank, having at one end a tool and at its opposite end a handle, a reciprocating member including lost motion mechanism operably associated with the shank and adapted to coöperate with the groove thereof, to impart relatively different degrees of rotary movement to the tool upon the reciprocal movement of said member from one end of the shank to the other.

6. In a tool of the character described, a grooved shank provided with a tool end and a handle end, a reciprocating member co-operably associated with the groove of said shank, said reciprocating member being provided with a lost motion mechanism, whereby movement of said reciprocating member along the shank in one direction will impart to the tool, a predetermined rotary movement and movement in the opposite direction will impart to said tool a relatively different predetermined rotary movement in a reverse direction.

7. In a tool of the character described, a spirally grooved shank, a tool end fixedly connected therewith at one end, a handle mounted at the opposite end and independently movable thereof, a reciprocating lost motion device mounted upon the shank in operable association with the spiral groove thereof, said reciprocating device adapted to impart differential degrees of rotation to the tool end, sequentially in alternate directions.

8. A tool of the character described, com-

prising a spirally grooved shank, an operating tool end, a relatively movable handle portion, and limiting stops adjacent its ends, a reciprocating member provided with lost motion mechanism operably associated with the grooved shank, said reciprocating member adapted on its full downward movement to impart a predetermined degree of rotation to the tool end and upon its full upward movement to impart a greater predetermined degree of rotation in reverse direction.

9. A tool of the character described, comprising a grooved shank portion provided with a relatively movable handle, a fixed tool end, a reciprocating member operably associated with the shank, and limiting stops on the shank for limiting the movement of the reciprocating member, said reciprocating member comprising a sleeve provided with a pin or projection operating in the groove of the shank and a circumferential cutout portion, a hand grip or sleeve provided with a pin or projection operating in the cutout portion of the first-mentioned sleeve, said pin adapted to coöperate with and impart to said sleeve a relatively small degree of rotation, upon the rectilinear movement of the hand grip or sleeve along the shank, where-
30 by differential rotary movements may be imparted to the tool end.

10. A tool of the character described, com-

prising a grooved shank, a reciprocating member cooperating therewith adapted to impart rotary movement thereto, said reciprocating member being provided with a lost motion mechanism, comprising inner and outer sleeves, the inner sleeve operably engaging the grooved shank and provided with two series of teeth in staggered relation, one series of teeth being at right angles to the opposite series of teeth, and both series of teeth being separated from each other, a pin or projection carried by the outer sleeve coöperating with said teeth and adapted to impart to said inner sleeve a partial rotary movement independent of and along the shank, said partial rotary movement comprising lost motion occurring during the movement of the reciprocating member along the shank in one direction whereby a definite predetermined rotary movement is imparted to the tool end, said mechanism operating when moved in reverse direction to impart to said tool end a greater predetermined rotary movement in reverse direction.

In witness whereof I have hereunto set my hand in the presence of two subscribing witnesses.
